UNITED STATES PATENT OFFICE.

JUDSON B. HURD, OF BROOKLAND, DISTRICT OF COLUMBIA.

VENDING-MACHINE.

No. 798,794.

Specification of Letters Patent.

Patented Sept. 5, 1905.

Application filed May 11, 1904. Serial No. 207,387.

To all whom it may concern:

Be it known that I, JUDSON B. HURD, a citizen of the United States, residing at Brookland, in the District of Columbia, have invented certain new and useful Improvements in Vending-Machines; and I do hereby declare the following to be a full, clear, and exact description of the invention, such as will enable others skilled in the art to which it applies to make and use the same.

One object of my invention is to provide a vending-machine for general store service that will enable the cashier or attendant to see the money which is paid for the goods before the goods are received by the customer, thus saving the merchant the danger of having his goods taken by the deposit of a slug or false coin, as is often done in the use of the ordinary slot-machine.

I show in Figure 1 one of my machines sitting on a counter with a coin-chute leading from it to the cashier's desk, also a cord from the desk to the machine. The machine is filled with articles wrapped ready to be delivered, and a sample is shown under a glass cover on top. When the customer deposits his coin in the slot X and moves the crank, the coin shoots over to the cashier's desk, and as soon as she can glance at the coin and pull the cord the article is delivered to the customer through the opening O. A large number of these machines may lead to one cashier's desk, and one person may serve forty or fifty customers within a minute. Fig. 2 is a vertical section of the main body of the machine. Fig. 3 is an enlarged elevation of the coin-ejecting mechanism. Fig. 4 is a horizontal section on line 4-4 of Fig. 2. Fig. 5 is an enlarged detail section showing means for locking the revolving case; Fig. 6, an enlarged section taken on line of the crank and through the pulley r. Fig. 7 is a section view on line 7-7 of Fig. 6. Fig. 8 and Fig. 9 are views similar to Fig. 3, showing other positions of the operating parts. Fig. 10 is a detail elevation of parts shown in Fig. 3; Fig. 11, a detailed perspective of the main portion of the device.

Referring to the drawings by reference-letters, A designates a stationary wooden base for the machine. On top of this base is an iron plate u, which supports a central standard b. On this standard revolves a circular case B, which is composed of a solid center piece B' and a series of pigeonholes B". These pigeonholes are formed by eight upright par-

titions C and by cross-partitions d. The cross-partitions are set on an incline to form the thread of a screw and are also made to extend a little farther from the center of the case 60 than the upright partitions. Ball-bearings e may be used to make the case revolve more easily.

Fixed to the base A is a metallic casing D, which surrounds the whole machine, except an opening up and down the front the width of a tier of pigeonholes. This opening is covered by a leather belt F. This belt extends entirely around the machine, being supported by rollers A' and A", the base and cover being cut away for the rollers and belt. The belt carries a metallic frame f, which leaves an opening O, through which an article may be taken from a pigeonhole of the case. The frame f has double flanges at the sides to engage with the edges of the casing D to hold the frame in place. It is also provided with a pin g at each corner, which pins extend inward to engage with the curved upper and lower partitions of the pigeonholes and prevent the frame and belt from moving up or down except as the case B is revolved.

Pivoted to the stationary cover E on its under side is a lever H, and on the top of the revolving case are a series of sloping lugs or catches l, adapted to engage the lever H as it passes in one direction and to allow it to slide over as it moves in the other direction. A spring m holds the lever H normally in the position shown, but allows it to be swung 90 enough to turn the case B the width of one pigeonhole. Fig. 1 shows the cord n, attached to the end of lever H and passing under the pulley p and extending to the cashier's desk, where it terminates with a ring q for handle. In another form of my machine this cord may pass over the pulley p and be fixed to pulley r, so as to allow the case to be turned as the coin is ejected. The turning of the case one space brings the opening O in front of another pigeonhole and allows the customer to remove the article therefrom.

The mechanism for ejecting the coin is supported by the upright wooden piece G, to which is fixed a bearing for the short cross-shaft h. Swinging loosely on this shaft is the long arm i, and rigidly fixed to the shaft is the short arm j. These arms are connected by spring k.

From the front of the machine a coin-chute 110 S reaches in past the shaft h and through an opening in wooden piece G and terminates

where it discharges the coin in the jaws formed by the part S' and the end of the curved channel S^2 .

The crank R by means of the bevel-gearing

- 5 R' turns the shaft h and the arms i and j . The inwardly-extending pin i' on arm i , being adapted to follow along the curved channel S^2 , carries with it the coin. When the coin has reached the position shown in dotted lines 10 in Fig. 3, the pin i' on the short end of arm i is engaged by notch L' in the dog L , and the arm i is arrested in its movement, while the arm j continues to move (stretching the spring k) until the pin j^2 strikes the outward 15 end of dog L and releases the arm i , which by the action of spring k shoots the coin up to the cashier's desk, if the coin-chute S^3 is extended that far.

Instead of ejecting the coin to a distance it

- 20 may be thrown up into a shorter chute, as shown in Fig. 3, and caused to turn back and lodge in a receptacle S^4 with glass on each side, where it will attract the attention of the customers and of an attendant that may be 25 on the other side of the counter. From this position the coins may be released one at a time by the lever P , which is operated by the same pin that carries the coin up the chute S^3 . In this case the article may be released to the 30 customer by the attendant pulling the cord n or by such other means as the nature of trade, &c., may suggest.

Pivoted to the under surface of the cover E is a hook t , which is adapted to drop into the 35 openings t' in the top of the revolving case and prevent the case being turned forward without moving the lever H . The lugs l keep it from being moved backward.

- To fill the case with articles for sale, a key 40 is inserted in the keyhole u at the rear of the machine, and by it the lever H is elevated, so as to allow the case to be turned backward. The case is then turned back one space at a time by hand through the opening O , and at 45 each movement an article is deposited in the pigeonhole. When the process of filling is completed, the key is removed from the hole u and the machine is thereby locked. The hook t is so placed in reference to the lever H 50 that with the movement of the latter forward the former will be lifted out of the openings t' , which allows the case to be turned forward by pulling the cord n , but not otherwise.

A ratchet-wheel v on the crank-shaft w and 55 a pawl on the metallic casing D prevent the crank being turned backward.

The mechanism shown in Figs. 3, 8, 9, and 60 10 is used as a means for sending the coin to the cashier's desk; but any other suitable means may be employed.

I claim—

1. In a vending-machine, the combination of means at a sales-counter or purchaser's station, for holding an article of merchandise ready 65 to be delivered to a purchaser when paid for;

a pay-receptacle related to said article-holder and adapted to receive the pay for said article; a means of communication between said pay-depository and a cashier's desk, with means for the transmission of the pay check 70 or coin between said points; and means of communication between the cashier's desk and the purchaser's station for the release of said article of merchandise to the purchaser.

2. In a vending apparatus of the kind described, means of communication between distant points as a purchaser-station with a cashier-desk, means at the purchaser-station for holding an article of merchandise ready to be delivered when paid for, means to prevent 80 said article from being removed from said article-holder, a pay-receptacle related to said article-holder and adapted to receive the pay for said article; in combination with means for carrying the pay, check, or coin from said 85 receptacle to the cashier-desk, and means controllable from the cashier-desk for releasing said article to the customer.

3. In a vending apparatus of the character described, means of communication between 90 distant points as a sales-counter or purchaser-station and a cashier-desk out of arm's reach of each other; means at the purchaser-station for holding articles of merchandise ready to be delivered to a purchaser; means to prevent 95 said articles from being taken without being paid for; and means under the control of an attendant at the cashier-desk for releasing said articles to the customer.

4. In a vending apparatus of the character described, means of communication between distant points as a purchaser-station and a cashier-desk out of arm's reach of each other; article-holders at the purchaser-station adapted to hold articles of merchandise on deposit 100 ready to be delivered to a purchaser when selected and paid for; a pay-receptacle related to said holders and adapted to receive the pay for said articles; means to prevent the articles from being taken without being paid for; means to enable an attendant at the cashier-desk to inspect the pay for an article before the article is delivered to the purchaser; and means controllable from the cashier-desk for 110 releasing an article from the holders.

5. In a vending apparatus of the character described, means at the purchaser-station for holding and exhibiting articles of merchandise for sale; means whereby the purchaser may communicate to an attendant at a distant point the selection of an article for purchase; and means operable by said attendant at said point for releasing said article to the purchaser.

6. In a vending apparatus of the character described, means for holding articles on deposit ready to be released to a purchaser when paid for; means whereby a customer may indicate his desire to purchase one of said articles by depositing pay for the same; and 125 130

means whereby the pay-check, or coin may be examined by an attendant before the article is released to the customer.

7. In a vending-machine, an article-holder at the delivery-point or purchasing-station adapted to hold an article on deposit to be released to a purchaser when paid for; a pay-inspection point and means to enable an attendant to inspect the pay before the article is released from said holder; in combination with means, under the control of the attend-

ant, for releasing the article; and means to prevent the article from being removed from said holder without the operation of said releasing means.

In testimony whereof I affix my signature in presence of two witnesses.
